UNITED STATES PATENT OFFICE.

WILLIAM FRIEDMAN, OF PRINCEVILLE, ILLINOIS.

COMBINED WINDOW STOP AND WEATHER STRIP.

Application filed April 9, 1923. Serial No. 630,695.

My invention relates to a combined window stop and weather strip.

The object of my invention is the provision of a combined window stop and weather strip which permits carrying of the conventional sash members and balance means entirely within the formal jambs.

Another object of my invention is the particular means of relating the window stop means and the weather strip with relation to the sash members.

A still further object is the provision of a single means wherein there are combined a window stop and a weather strip, the said members being positioned in such manner that the conventional sashes may be assembled with the jamb members without utilizing either the space beyond said jambs or the mounting of the window stop at the ends of the window sashes.

Other objects of my invention will appear in the following specification in connection with the annexed drawings in which Figures 1 and 2 are front elevations of the outside and the inside of a window utilizing my present combined window stop and weather strip.

Figure 3 is an end elevation in vertical section showing in detail the particular mounting of the weight members, sashes, etc.

Figure 4 is an enlarged sectional view in plan showing in detail the arrangement of my combined window stop and weather strip with relation to the sash and jamb.

Referring to the drawings:

In Figures 1 and 2 are shown the outside and inside of a window equipped with my device. The conventional outer and inner casings are shown at 10 and 11 respectively with the formal jamb member 12 disposed there-between. I have described but one side of the window, but of course, there is a similar construction at the other.

At 13 and 14 are shown upper and lower portions of the window frame. The upper and lower sashes appear as 15 and 16 and are conventional in form. However, it may be said that these sashes are of sufficient size that they fit snugly within the opposed jamb members; in other words, my invention is adapted to co-operate with the sash and jamb members in such relation that no space is required between the ends of the window and the jambs for the disposal of the weight members and in a like manner

no utilization of the space beyond the jambs is necessary.

In Figure 4 perhaps the clearest showing of my particular device is made wherein I have shown said device in connection with both the upper and lower sash members. For brevity it is thought only necessary to describe one of the sides, inasmuch as the description for one will suffice for both, the only difference being that a similar structure would be assembled on the other side of the window. There is another exception in that the pulley for the lower sash is made somewhat larger than that for the upper. This is clearly shown in the drawing at 25. A stamped sheet metal plate is shown at 17, this plate member having formed therein the housing 18 at one end. The metal sheet then follows the jamb a short distance and finally has a lip 20 projecting into a suitable receptacle or groove 23 providing an attached or rather combined weather strip. The sheet metal housing 18 is attached at one end to the outside casing 10 in a suitable manner and the remainder of the sheet metal member is further attached to the jamb member at 21 and 22 respectively. The positioning of said sheet metal plate with relation to the sash 15 is clearly shown and the weather strip or rather lip 20 is adapted to engage a corresponding groove 23 upon the edge of said sash.

Pivotedly mounted as at 24, in the upper portion of the sheet metal housing 18 is a pulley 25, a weight member 26 is disposed within the casing and adapted to move upwardly and downwardly therein by means of the rope or cable 27 which is attached to the upper portion of the weight at one end and at its other to the opposite end of the sash as at 28.

The operation of my device is as follows and is similar to the operation of all window stops:

The manual movement of the sash member is permitted due to the balancing thereof by means of the weights disposed in the metal casing, with the result that the sash may be raised or lowered to any desired point and maintained in said position by the heretofore described balance means.

As has been described, my sheet metal plate not only acts as a housing for the weight members, but also as a metal weather strip and runner for the sashes with the

result that the assembly of my particular structure permits the inclusion of a window stop mechanism and weather strip at the same time.

5 What I claim is:

The combination with a window frame and sash member of window stop mechanism, a sheet metal portion adapted for ready attachment to the window jamb, said sheet metal portion including at one end a container for the sash balance mechanism, said container having a flange portion extend-

ing the entire width of the sash, said flange portion limiting the position of the container with relation to the parting strip, 15 the pulley of said sash balance mechanism being pivoted in the container and lying parallel with the jamb, and said flange portion having a raised member thereon acting as a combined runner and weather strip 20 therefor.

In testimony whereof he affixes his signature.

WILLIAM FRIEDMAN.
